US00D477541S

(12) United States Design Patent (10) Patent No.: US D477,541 S
Barker (45) Date of Patent: * Jul. 22, 2003

(54) REFRIGERATOR THERMOMETER

D244,360 S * 5/1977 Van Kersen D10/57

(75) Inventor: W. J. Stephen Barker, London (GB)

* cited by examiner

(73) Assignee: B & H Liquid Crystal Devices Ltd.,
London (GB)

Primary Examiner—Antoine Duval Davis
(74) Attorney, Agent, or Firm—Heller Ehrman White &
McAuliffe LLP

() Term: 14 Years

(57) CLAIM

(21) Appl. No.: 29/161,673
(22) Filed: May 29, 2002

The ornamental design for a refrigerator thermometer, as shown and described.

(30) Foreign Application Priority Data

Nov. 29, 2001 (FR) 01 6974

DESCRIPTION

(51) LOC (7) Cl. 10-04
(52) U.S. Cl. D10/57
(58) Field of Search D10/57; 374/162,
374/141, 161, 208, 142, 163; 116/206,
207, 216

FIG. 1 is a top view of the refrigerator thermometer; and,
FIG. 2 is a side view of the refrigerator thermometer.

The front and back surfaces of the refrigerator thermometer are flat and unornamented. The circumference is unornamented.
The drawing is lined for color.

(56) References Cited

U.S. PATENT DOCUMENTS

D239,262 S * 3/1976 Van Kersen D10/57

1 Claim, 1 Drawing Sheet

FIG. 1

FIG. 2